BURGLAR ALARM SYSTEM

Edwin O. Walker, Chicago, Ill.

Application March 1, 1937, Serial No. 128,353

7 Claims. (Cl. 177—314)

My invention relates in general to an improved burglar alarm system and especially to a protective system for stores or other premises including not only a visual or audible alarm but also the release of tear gas to prevent theft and unauthorized entry of the premises.

A great many burglar alarm systems have been designed and are in use which provide alarms when a protective circuit is broken by unauthorized entry. Such an alarm will only attract the attention of a watchman or an officer on the beat, but is usually ineffective to prevent burglary, especially in small stores such as dress shops, jewelry shops, fur stores, etc., where goods of great value can be seized and carried away in a short interval of time and before help arrives. This is true whether an alarm is sounded on the premises or at a remote point such as a general alarm station.

The system of my improved design incorporates not only the alarm feature but also the additional feature of setting off tear gas bombs on the premises whenever the premises are forcefully entered. In systems using tear gas it is essential that every precaution must be taken to insure against the accidental discharge of tear gas bombs by any inadvertent operation of the system by employees either after or while the alarm system is being set. This is extremely important when tear gas is used because an accidental discharge of a gas bomb would drive every one from the premises for an hour or more before the gas could be dispersed.

In addition to providing an efficient alarm system in which an alarm is sounded and gas is automatically released by an unauthorized entry, I have provided a system of safe guards against accidental operation which makes the system completely foolproof and also provides a complete check and test of the system each time it is set, without danger to the operator.

The safeguards are arranged in such a manner that a definite sequence of operations is required before the alarm system can be set and whenever any accidental operation is performed an alarm is sounded which gives notice thereof and permits time for the store owner or manager to shut off the system before a second action takes place and thus prevent the release of tear gas. The arrangement of the system and the operations required in setting it into operation will be pointed out below by reference to the accompanying drawing.

The drawing shows a schematic diagram of the complete circuit of my improved system. In an

installation the apparatus would consist of four main parts, namely,

1. A control cabinet housing the dry cell batteries and relays, and having the switches mounted thereon.

2. A loud ringing alarm bell mounted somewhere near the premises.

3. Tear gas guns or bombs distributed throughout the premises, and

4. Gas contacts or trip switches set throughout the premises in position to be tripped by an intruder either walking across the floor or removing merchandise and in addition the usual alarm circuit passing through tin foil strips on all windows which will be severed whenever a window is broken, and through contacts on doors, transoms, etc., which will be opened in case they are forced.

In the drawing the alarm circuit just mentioned is indicated by the *x* wiring shown to the right of relay D between points 1 and 2 and 3 and 4. The trip switches which I have mentioned as being set around the premises are shown diagrammatically at 5 and 6 as multiple contacts any one of which will close its circuit. The loud ringing bell or general alarm signal is shown at 7. Two circuits are shown each including a plurality of gas bombs or guns. These guns are indicated only diagrammatically at 8 and 9 and may of course be any type of gun or bomb adapted to be set off or exploded electrically. One type of such bomb is described in U. S. Letters Patent #2,068,159 granted January 19, 1937.

In the drawing I have shown two batteries B' and B² one of 4.5 volts and the other of 7.5 volts with their positive poles grounded for convenience of illustration. In practice one battery may be used if desired and direct wire connections will probably be used in place of ground.

The steps which must be taken to set the alarm system will now be described in their proper sequence. The switch A is first operated to close contacts 10 and 11. This operation completes a circuit from ground through springs 10 and 11, armature 12 and its back contact, springs 13 and 14, lamp L, and through battery B' and back to ground. Lamp L lights momentarily over this circuit. At the same time however another circuit is completed from ground through springs 11, wire 15, wire 16, springs 17 and 18, terminal 3, *x* alarm wiring, terminal 4, relay D, terminal 2 and *x* alarm wiring to terminal 1, variable resistance R, ammeter AM, and through battery B² to ground. Relay D will energize over this circuit.

cuit provided the x alarm winding is intact and battery B^2 is in proper condition. If the alarm winding is complete then relay D energizes to open the back contact of armature 12 and close 5 with its front contact. The opening of the back contact opens the previously traced circuit of lamp L so as to notify the operator that the x alarm wiring is in condition. The momentary operation of lamp L also indicates that switch B 10 is in normal position. The closure of the front contact of relay D completes a new circuit of relay D exclusive of the springs of switch B, from ground through armature 11 and 10, armature 12 and its front contact, and through alarm wiring 15 and relay D over the previously traced circuit to battery B^2 and ground. The variable resistor R is used to maintain the proper current flow in relay D as battery B^2 deteriorates.

When switch A was thrown a circuit was also 20 prepared from ground through springs 11, wire 19, through sets of contactors 5 and 6 in parallel, armatures 20 and 21 and their back contacts, resistance R' , and through low resistance bell or 25 buzzer 22 to battery B' and ground. If any of the contactors 5 or 6 should be closed and therefore not properly set then the above traced circuit would be completed and the buzzer 22 would ring to warn the operator not to proceed farther with the setting of the systems until the contactors were properly set and all open.

Assume that the system is properly prepared and the lamp L lights only momentarily and buzzer 22 does not ring. The operator will then 30 operate the switch B to its "on" position to open springs 17 and 18 and to change spring 13 from contact with spring 14 into contact with spring 23. The opening of springs 17 and 18 opens the original circuit through relay D so that it cannot reenergize until switch B is again normal, 35 and the opening of springs 13 and 14 opens the circuit of lamp L. The closing of springs 13 and 23 prepares a circuit for relay E extending from ground through springs 11 and 10 of switch A through armature 12 and its back contact (now open), springs 13 and 23, relay E, and battery 40 B' to ground. Relay E therefore does not energize as long as relay D is held up by current in the alarm circuit x wiring.

Should any of the preceding tests have failed 45 to function that is, if relay D should be back due to the alarm wiring being open, then the relay E would energize over the above traced circuit through the back contact of relay D. If relay E should energize and move its armatures 20, 21 and 24 to close their front contacts, then a circuit is completed for the loud ringing bell 7 from ground at springs 11 of switch A, wire 15, armature 24 and its front contact, and bell 7 to battery B' and ground. Also if relay D is energized but a gas contactor 5 or 6 should close then a circuit would be completed from ground through springs 11, wire 19, a contactor 5 or 6, armature 20 or 21 and its front contact, spring 25 or 26 of switch C and its normal contact 27 or 28, resistance R' , and buzzer 22 to battery B' and ground.

Should all tests be satisfactory and neither of the bell 7 or buzzer 22 operate after switch B has been thrown then the operator may proceed 50 with the last step in the setting of the system which is the operation of switch C to cut the gas bombs in circuit. The operation of switch C switches springs 25 and 26 from contact with springs 27 and 28 and thereby from buzzer 22 55 and into contact with springs 29 and 30 which

are connected by wires 31 and 32 through a series of gas bombs or guns 8 and 9 to battery B^2 .

The system is now fully set and ready for any forced entry. The operator must then have the usual means for leaving the premises by short circuiting a door circuit until he has passed out and locked the door at which time the short circuit is removed. In the diagram I have shown two sets of gas bombs and two sets of gas contactors, each set of bombs and the associated contactors in circuit therewith may be in one room or section and it will be understood that as many sets may be provided as are desired to sectionalize the system or the operation of any contactor may be arranged to set off the whole series of bombs.

After the system is set it will function as follows. Anyone entering the premises will first break the alarm wiring at some point in the x wiring between terminals 1 and 2 or 3 and 4 and thus break the circuit of relay D. Relay D 20 upon falling back will complete the circuit of relay E at the back contact of armature 12 and cause energization of that relay. Relay E, upon energizing, will immediately close the circuit of the loud ringing alarm bell 7 at armature 24 and 25 its front contact to sound a general alarm. Should the intruder be scared away by the alarm bell 7 no further operations will ensue. The energization of relay E in addition completes another point in the gas bomb circuits at armatures 20 and 21 and their front contacts so that these circuits are now complete except for the gas contactors 5 and 6. Should the intruder continue and enter the premises in an effort to obtain plunder before help can arrive then he will 30 operate one of the contactors 5 or 6 which are placed around the rooms in easily tripped position. The operation of a contactor such as 5 at this time will close a circuit from ground through springs 11 of switch A, wire 19, contactor 5, armature 20 and front contact, springs 26 and 30 of switch C, wire 32, gas bombs 9 in parallel, and battery B^2 to ground. The bombs will be immediately exploded by this closure of their circuit and tear gas will be released. If the intruder 35 attempts to escape by entering the section where contactors 6 are placed then the similar circuit of bombs 8 will be closed and they will also be exploded. Thus while gas is immediately released by forced entry it will be seen that the breaking 40 of a window by frost or other cause without entry of the premises will only sound the alarm bell 7 without releasing tear gas. Also in case one of the gas contactors is tripped without the alarm circuit having been broken, then the buzzer 45 22 will be sounded as a trouble signal without the release of tear gas.

In addition to the above features, I have also provided manual means for operating the system in case of a daylight raid. The switch F is shown 55 which has springs 33 for closing the circuit of alarm bell 7 and springs 34 and 35 for preparing a circuit for the gas bombs 8 and 9. This switch may be located in one of the offices or there may be several of such switches at different locations. After switch F has been thrown then a special 60 switch G may be operated to complete the circuit of the tear gas bombs over the obvious circuit from switch G and through springs 34 and 35 of switch F. The switch or switches such as G will 65 usually be under glass which must be broken before operation and having warning signs to warn employees that this switch should not be tampered with except in emergencies. Other manual switches may be provided as desired for 70 75

ringing bell 7 and operating the gas bombs simultaneously.

Having fully described the features of my invention what I consider to be new and desire to have protected will be pointed out in the appended claims.

What I claim is:

1. In a burglar alarm system, an alarm signal, gas discharge devices, a closed protective circuit, means in said circuit responsive to any opening of said circuit to control the alarm signal, a normally open circuit having means therein responsive to a closure of the circuit to operate said discharge devices, said last means inoperative to control said devices until the first means has operated, and means including contactors in said normally open circuit operative to control the means in said circuit to operate the discharge devices only after said first means has operated.

2. In a burglar alarm system, an alarm circuit, a relay in said circuit, gas discharge devices, a circuit containing normally open contactors for controlling said devices, an alarm signal normally controlled over said second circuit said relay operated by an opening of the alarm circuit, a second relay operated by the operation of said first relay to substitute said devices for the alarm signal for control over said second circuit, repeated operation of a contactor causing only the operation of said signal before the said second relay is operated and any operation of a contactor after the second circuit is prepared causing the explosion of said devices.

3. In a burglar alarm system, a protective wiring, a relay, gas discharging devices, a circuit including said wiring and said relay, a switch for closing said circuit, a signal, means controlled by said relay for operating said signal and maintaining it operated in case of a fault in said wiring, another circuit closed by the operation of said switch including a plurality of contactors, another signal operated upon operation of said switch in case any of said contactors are closed, a second switch, a circuit controlled by said second switch, a relay in said last circuit operated when the second switch is closed only when said

first circuit is open and the first relay deenergizes, a third signal operated when the second relay energizes, and a third switch operated to bring said gas discharge devices under control of said contactors.

4. In a burglar alarm system, gas discharge devices, a normally open protective alarm circuit, another normally open protective gas circuit having open contactors, means for setting the alarm system including switches for preliminarily closing both circuits, signals controlled by the closure of each circuit for indicating when the circuits are not set in proper condition, another switch for switching the circuits into final set condition, and means responsive thereafter to an opening of the alarm circuit and the closing of a contactor for sounding an alarm and exploding said gas discharge devices after the circuit has been placed in final set condition.

5. In a burglar alarm system, an alarm, gas discharge devices, an alarm circuit, another circuit having open trip contactors, means responsive to an opening of the alarm circuit for sounding the alarm, said means also preparing the other circuit, and the tripping of any contactor closing said other circuit to explode the gas discharge devices only after the alarm circuit has been opened.

6. A burglar alarm system as claimed in claim 5 in which said circuits are normally inoperative and there are a plurality of switches arranged to be closed in sequence to render the circuits operative, and signals arranged to be operated by the operation of each switch in case any of the circuits are not in proper condition to be set.

7. In a burglar alarm system, a protective alarm circuit, an alarm controlled over said circuit, gas discharge devices arranged in groups, a circuit for each group including contactors the operation of any one of which will explode the group of devices associated with that circuit, and means for preventing any operation of any contactor from exploding its group of devices as long as the protective alarm circuit is intact.

EDWIN O. WALKER.
